MACHINE FOR PRINTING FROM ENGRAVED PLATES OR DIES

Filed Oct. 14, 1921

2 Sheets-Sheet 2

UNITED STATES PATENT OFFICE.

FRED WAITE, OF INGLEWOOD, ENGLAND.

MACHINE FOR PRINTING FROM ENGRAVED PLATES OR DIES.

Application filed October 14, 1921. Serial No. 507,726.

To all whom it may concern:

Be it known that I, FRED WAITE, a subject of the King of Great Britain, and resident of Inglewood, Otley, in the county of 5 York, England, have invented a certain new and useful Improvement in Machines for Printing from Engraved Plates or Dies, of which the following description, having reference to the accompanying sheets of drawings, is a specification.

It relates to printing machines wherein dies or engraved plates are used, and more particularly to that class or type of said printing machines wherein the die or engraved plate during the printing process is face downwards and therefore the printed card, paper or the like is face upwards so that its printed surface is displayed to the attendant, and my said invention consists in 15 so mounting the said printing die and constructing and arranging the varied parts and guiding surfaces in connection therewith, that after each impression has been made the die begins to move from its position where same has been carried out, and then turns from said latter position to move up inclined guides to be taken to the position where the inking, scraping and wiping processes are carried out. During the ascending part of its movement its engraved or printing surface is displayed to the attendant as it also is after said inking process has been completed when it is descending to finally return to its printing position. By 20 thus making use of these compound movements of the die the attendant is enabled to detect any irregularities or defects that may occur and attend to them accordingly. In addition to the features above described I 25 so mount and arrange the printing die that I am enabled to use in connection therewith, a device which will automatically remove or strip the printed card, paper or the like from the die after the printing operation.

In the accompanying sheets of drawings which are illustrative of my invention,

Fig. 1 is a part sectional side elevation of sufficient of a machine to show the application of my improved devices.

Fig. 2 is a front elevation of certain of the parts shown by Fig. 1.

Fig. 3 is a front view of the die carriage and the parts which support same.

Fig. 4 is a side elevation of the parts shown by Fig. 3.

Fig. 5 is a sectional plan of certain parts shown by Fig. 1, said parts being made use of for stripping the printed card or sheet from the die after the printing operation.

Fig. 6 illustrates in detail a detachable 60 part of the devices shown by Fig. 5.

Fig. 7 illustrates the stripping device in its highest position which it assumes to allow greater freedom for feeding the sheets of paper or the like to the machine.

Fig. 8 shows the same device in its mid-position when the impression is to be made.

Fig. 9 shows the same device in its lowest position where it will have stripped the printed sheet from the die prior to the movement of the die carriage.

Fig. 10 is a sectional elevation showing a part in detail hereinafter described.

A represents the side frame of the machine, B the main driving shaft of said machine and C the cross head or member which binds the two sides A together.

In carrying my invention into effect I make use of a carriage 2 for the die or engraved plate 3, said carriage being of such 80 formation that I may have the runner or antifriction bowls 2^a upon which it is mounted, supported within the guiding grooves 4^a of the inclined guides 4 under such conditions that when they are in position (as shown by Fig. 1) for giving the impression, said carriage 2 and the die 3 which it supports, are supported by the cross head C which withstands the upward pressure of the counter part when said impression is 85 being taken. To enable the cross head C to afford this support to the carriage 2 and yet permit the early upward movement of said carriage, I form the lower edge of said crosshead C with a stop h and a higher part 90 k, for the lower part s and the stop t respectively on the carriage 2 to take against.

The impression is given by a rising and falling plunger carrying a counterpart operated in any well known manner.

This carriage 2 is so shaped and constructed that the runners 2^a may operate within the groove 4^a of the guiding inclines 4 in order that after each impression the operating parts may carry such carriage 2 105 from the position shown in Fig. 1 and full lines Fig. 4, to move from its horizontal position and turn at the part b so as to travel up the inclined portion of the inclined guides 4 into the position shown in broken 110

lines Fig. 4. The inking of the die is effected by the messenger roller 6 carrying the ink from the feed roller 7 to the die 3.

When the die 3 is moved from the printing position as hereinbefore described to the position shown in broken lines Fig. 4, during its ascent of the inclined part of the guiding track or rail 4, its printing or engraving surface is displayed to the attendant.

The taking of the die up the inclined track enables the operator to have a full view of the inking, scraping and wiping operations.

15 After the inking operations have been performed, on the die 3 descending it encounters appropriate blades or scraping devices 8 which remove the superfluous ink from said die in such a manner that the 20 ink thus removed may travel down the shoot 9 back to the ink trough 10. And during the further downward travel of the die towards the printing position it encounters the wiping pad 11 (over which 25 travels the wiping paper in steps or stages as is well understood) where the final wiping operation is carried out in well known manner.

The die thus prepared is brought back to 30 its printing position as shown by Fig. 1.

The operating of the die is effected by means of the crank pin 12 which is rotated about the main shaft B, and to this crank 12 is connected a rod 13 which actuates the 35 operating lever 14 so that said lever 14 may, by the arm 15, cam 16 and spring arrangement 16^a together with the connecting rod 17, operate the levers 18 which are pivoted at e, thus the carriage 2, by being connected 40 to the levers 18 (by connecting rods 19) is made to move as desired while the required dwell or rest during the printing operations, is effected by the dwell or rest of the levers 18 which is brought about by the actions of the arm 15, upon the yielding 45 spring 16^a and connecting rod 17, when the carriage 2 has reached the position shown by Fig. 1. On reaching this position the carriage 2 is prevented from further 50 movement towards the front of the machine by means of the stop piece 30 which is fixed upon the cross head C (see Figs. 2 and 10). This stop piece 30 arrests the carriage in the exact position for the die 3 to be 55 brought immediately over the counter part beneath, which is then raised to take the impression. When the carriage 2 has reached the stop piece 30 as stated, the spring 16^a will be compressed by the further 60 motions of the lever 15 and this compression enables the spring to retain the carriage 2 in position against the stop piece 30 although the levers 15 continues to complete its full movement. By arranging the 65 die carriage 2 to travel up the inclined

track on the guides 4, said die carriage follows a path which nearly coincides with the curved path of the outer ends of the levers 18, consequently the movements of said carriage are more efficiently performed 70 and that while yet keeping the arms 18 comparatively short.

In connection with the die 3 I make use of two arms 20, 20^a which are supported by the vertical guiding rods 21, 21^a upon 75 which rods are mounted the yielding springs 22, 22^a. These arms 20, 20^a carry a frame 23 which is detachable by reason of the slots d made in the projecting ends illustrated by Figs. 5 and 6, taking over 80 the heads of pins f carried by the arms 20 while the front edge of said frame 23 is held in position preferably by spring clips 24 although other devices may be made use of for said purpose, thus a large or smaller 85 paper or other mask may be mounted on the frame 23 to meet the requirements of larger or smaller dies as will be understood.

The varied movements of the arms 20, 20^a, and the parts which they carry, are obtained from the rotary shaft 25 which derives its motion from the shaft B through any appropriate gearing. On this shaft 25 is fixed a cam 26 which actuates a lever 27 fixed to the cross shaft 28. Also fixed to 90 the cross shaft 28 are the lever arms 29, 29^a, which are arranged to have their outer ends to press upon the upper ends of the rods 21, 21^a respectively. By these means the descending movements of the arms 20, 20^a are 95 effected by the arms 29, 29^a while their ascent is brought about by the recoil of the spring 22, 22^a. Such being the nature and object of my said invention, what I claim 100 is:—

1. In a die printing machine, a carriage, a die mounted upon said carriage face downward, guiding rails for said carriage, said rails having certain parts arranged to hold the carriage in the horizontal plane and the other parts at an angle to said horizontal plane, connecting rods and pendant levers for operating said carriage, a connecting rod coupled to said pendant levers, a yielding spring on said connecting rod, a cam lever 105 for operating said connecting rod and means for transmitting motion to said cam lever.

2. In a die printing machine, a die mounted upon a carriage face downwards, said carriage, rails for guiding and retaining said carriage in horizontal and inclined paths, a frame for stripping the printed sheet from the die, rods for supporting said frame, springs mounted upon said rods, levers for actuating said rods, a cross shaft 110 upon which said levers are mounted, another lever mounted on said shaft for operating same and a cam for operating said lever.

3. In a die printing machine, a die, a 115

carriage upon which said die is mounted face downwards, guiding rails along which the carriage is moved, said rails having horizontal portions and portions at an angle thereto, connecting rods and lever arms for operating said carriage, said lever arms being mounted so that their outer ends may follow the path described, and lever and cam mechanism for operating said lever arms.

4. In a die printing machine, a die mounted face downwards, a carriage for said die having its upper surface of step like formation, framework formed to receive said step like shape of carriage, horizontal and inclined guiding rails along which said carriage is moved, and means for operating said carriage.

15

FRED WAITE.
